UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

TRIMMING-MACHINE.

1,057,071.

Specification of Letters Patent. Patented Mar. 25, 1913.

Application filed July 29, 1909. Serial No. 510,234.

To all whom it may concern:

Be it known that I, BENJAMIN F. MAYO, a citizen of the United States, residing at Salem, in the county of Essex and State of Massachusetts, have invented certain Improvements in Trimming-Machines, of which the following description, in connection with the accompanying drawings, is a specification, like reference characters on the drawings indicating like parts in the several figures.

This invention relates to trimming machines and particularly to trimming machines of the type commonly employed in the manufacture of boots and shoes in which the trimming operation is performed by a rapidly rotating cutter.

According to the usual practice of manufacturing shoes, the shoe is sent to the operator to be trimmed with the sole already having substantially the shape desired in the finished shoe. The sole edge, however, is still rough and uneven, and before the shoe is finished the edge must be trimmed, inked and burnished. In the trimming operation, according to the present practice, the operator or "trimmer" holds the shoe with the sole edge against a rapidly revolving cutter and draws it past the cutter, guiding the shoe by his eye in such a manner as to maintain substantially its existing contour. To guide the shoe so as to produce a sole of correct shape with a smooth, even edge surface, and at the same time avoid trimming too closely to the stitches, particularly in trimming shoes having pointed toes, requires a high degree of skill and experience on the part of the operator.

The present invention aims broadly to facilitate the trimming operation, and more specifically, to provide an improved attachment, hereinafter termed a gage, for a trimming machine by which the operator may regulate to a nicety the depth of cut of the tool; which shall positively limit the depth of cut during operation on certain portions of the work; which shall be capable of various adjustments, and which may be readily moved away from the cutter to permit inspection or removal of the latter.

The particular manner in which the above objects are attained will be clear from the

detailed description of a preferred embodiment of the invention hereinafter set forth.

Briefly stated, the invention in the embodiment illustrated in the accompanying drawings comprises an adjustably mounted frame carrying a stationary edge rest, a movable edge rest and a stop-controlling finger, each of the edge rests and the finger being arranged to engage the work, and an adjustable stop mounted on the finger and adapted to engage the movable edge rest and limit its motion during operation on certain portions of the work.

The invention also comprises other features of construction and operation and certain combinations and arrangements of parts which will be hereinafter described and for which protection will be sought in the appended claims.

In the accompanying drawings, Figure 1 is a view in front elevation of the gage applied to a trimming machine. Fig. 2 shows in front elevation the positions of certain parts of the gage as the cutter operates along the side of the sole. Fig. 3 is a view similar to Fig. 2 showing the cutter trimming around the toe portion of the sole. Fig. 4 is a perspective view of a detail later to be referred to. Fig. 5 is a view in side elevation of the parts supporting the stationary edge rest.

The gage mechanism is supported by a pin 2 projecting from the standard of the trimming machine, on which pin is adjustably mounted a gage-carrying head 4 having a set screw 6 for holding the head in an adjusted position. By turning the head on the pin 2 the entire gage mechanism may be swung away from the cutter to permit removal of the latter; and the head is retained in either its operative or inoperative position by two spring pressed plungers mounted in the head, one of which is shown at 8, Fig. 4, and which snap into suitable recesses in the standard of the machine. The turning movement of the head 4 relatively to the pin 2 is limited by stop pins 10 and 12 carried respectively by the head and standard. The head is provided with a slideway 14, as shown in Fig. 4, in which is received a frame 16 that supports the remaining members of the gage. The frame consists of a casting

and a plate 18 secured thereto by screws 20. The frame may be adjusted toward and from the cutter in a plane transverse to the shaft of the latter by means of a short lever 22 fulcrumed on a post 24 rigidly fixed in the hub 4 and extending through a slot in the frame. A pin 26 projecting from the frame is positioned in an aperture in the handle 22, and by moving the right hand end of the lever, as seen in Fig. 1, up or down, the pin 26 and consequently the frame 16 will be moved in the slideway 14. When the desired adjustment has been made the frame may be locked in its adjusted position 15 by a thumb nut 28.

A projection 30 extends to one side of the frame 16 and is drilled to receive a pin 32 having a transverse aperture 35 in which the upper end of the stationary edge rest 34 is adjustably secured. A helical spring 36, see Fig. 5, positioned between the projection 30 and an arm 38 rigidly mounted on the pin 32, holds the pin in its forward position and serves to prevent the edge rest 34 from 25 sliding through the pin 32 after it has been adjusted therein. The edge rest 34 normally occupies the position in which it is shown in full lines in Fig. 1, but may be 30 swung into the position indicated by the dotted lines when it is desired to remove the cutter as above mentioned. In order to 35 adjust the rest with relation to the cutter, a screw 40 is threaded through the arm 38 and abuts against a stop 42 on the frame-plate 18 and a lock nut 44 holds the screw in an adjusted position. A second edge rest 46 preferably of segmental form is positioned 40 at the side of the cutter opposite from the stationary rest 34 and is secured to the frame by an extension 47, which for convenience in manufacturing is formed integral with the edge rest, and a pivot pin 48 positioned in alignment with the axis of the cutter shaft. A spring 50, connected at one end to 45 the extension 47 and at its other end to a stationary arm 52 adjustably secured to the frame 16 by a screw 54, yieldingly holds the rest 46 in its forward position. The movement of the rest 46 on its pivot is limited by 50 a pin 49 which strikes the frame-plate 18. Located adjacent the edge rest 46 is a stop-controlling finger 56 pivoted to the frame at 55 58, and also yieldingly held in its forward position by a spring 60 secured to the stationary adjustable arm 62. A stop 64 is adjustably mounted on the finger 56 and said stop and finger constitute a locking device for the edge rest 46, the stop being arranged to engage the yielding edge rest 46 during operation on certain portions of the work to limit the movement of the latter. The point of engagement of the stop 64 with the rest 46 may be varied by adjusting the stop 64 on the finger 56 and also by varying 60 65 the effective length of the finger itself, which

is made extensible by the screw and slot construction shown at 66.

During operation, the "trimmer" takes the shoe in both hands and, starting at the shank, draws the sole edge across the cutter from left to right so as to take off a thin shaving. The edge rests materially aid the operator in accurately guiding the shoe to regulate the depth of cut of the tool: the edge rest 34 forming a fixed abutment on 75 which the sole edge may be rocked to bring the sole nearer to or farther from the cutter. The finger 56 and edge rest 46 each engage the sole and yield as the shoe is manipulated during the trimming of the side of the sole. 80 Fig. 2 indicates the position of the edge rests and finger during this operation. As the cutter approaches the toe portion of the sole the rest 46 and finger 56 each move forwardly, as they continue to engage the sole, 85 and as the pivots 48 and 58, about which respectively the rest and finger rotate, are widely separated, the path of movement of the stop 64 intersects the path of the rest 46. Consequently, the stop 64 will drop in behind the edge rest when the latter has moved forward to a certain point and thus limits the extent to which the sole edge can thereafter be crowded in between the ends of the edge rests 34 and 46, and hence limits the 90 depth of cut of the tool. In the position of the parts shown in Fig. 3, the edge rest is locked by the stop 64 and pin 49 against movement in either direction. The time in the relative movement of the edge rest 46 100 and finger at which the locking action takes place may be varied by adjusting the position of the stops 64 on the finger and also by varying the effective length of the finger itself by means of the adjustable connections 66; and by means of these adjustments the depth of cut of the tool may be controlled. As the shoe is further turned to allow the cutter to travel along on to the side of the sole again, the finger 56 will be 105 forced backward until the stop 64 is swung clear of the yielding edge rest when the parts will again occupy substantially the positions in which they appear in Fig. 2.

To permit inspection or removal of the 110 cutter it is merely necessary to swing the rest 34 from the full line to the dotted line position, Fig. 1, and then turn the gage-carrying head 4 in a counter-clockwise direction on the pivot 2 until the gage parts are clear 115 of the cutter.

Having fully described my invention, what I claim as new and desire to secure by Letters Patent of the United States is:—

1. A gage for a rotary cutter comprising 125 a movable rest and means for automatically locking said rest against movement during operation on certain portions of the work.

2. A gage for a rotary cutter comprising 130 a yielding rest and means constructed and

- arranged to automatically lock said rest against movement during operation on a certain portion of the work and to automatically unlock the rest during operation on another portion of the work.
- 5 3. A gage for a rotary cutter comprising a movable rest and work controlled means acting automatically to limit the movement of said rest during operation on certain portions of the work.
- 10 4. A gage for a rotary cutter comprising a movable rest and work controlled mechanism acting automatically to limit the movement of said rest during operation on certain portions of the work and means whereby said mechanism may be adjusted.
- 15 5. A gage for a rotary cutter comprising a yielding rest and means controlled by the work acting automatically to limit the movement of said rest during operation on certain portions of the work and to permit the rest to move freely during operation on certain other portions of the work.
- 20 6. In a sole trimming machine, a rotary cutter and a gage therefor, comprising a yielding edge rest and means acting automatically to lock said rest against movement during operation on the toe portion of the sole and to unlock said rest again when the side of the sole is reached.
- 25 7. In a sole trimming machine, a rotary cutter and a gage therefor, comprising a yielding edge rest and means capable of adjustment acting automatically to lock said rest against movement during operation on the toe portion of the sole and to unlock said rest again when the side of the sole is reached.
- 30 8. A sole trimming machine, comprising in combination, a rotary cutting tool, and means controlled by the work for limiting the depth of cut of the tool.
- 35 9. A sole trimming machine, comprising in combination, a rotary cutter and means controlled by the work for positively limiting the movement of the work toward the cutter.
- 40 10. A machine of the class described, comprising in combination, a rotary cutter, means for limiting the movement of the work toward the cutter and mechanism constructed and arranged to be operated by the work to modify the limiting action of said means.
- 45 11. A gage for the rotary cutter of a sole trimming machine comprising means for controlling the convexity of the sole edge during operation on the toe portion of the sole.
- 50 12. A gage for the rotary cutter of a sole trimming machine comprising means controlled by the drag of the edge of the sole, during the relative movement of the sole and cutter, for limiting the depth of cut of the tool.
- 55 13. In a sole trimming machine having a rotary cutting tool, a gage for said tool comprising means controlled by the work for limiting the depth of cut of the tool during operation on certain portions of the work.
- 60 14. In a sole trimming machine having a rotary cutting tool, a gage for said tool, said gage having means controlled by the work for limiting the depth of cut of the tool as it operates along certain portions of the work and mechanism whereby the depth of cut may be adjusted.
- 65 15. In a sole trimming machine, a cutting tool and a gage therefor having means controlled by the contour of the sole for limiting the depth of cut of the tool.
- 70 16. A gage for a rotary cutter, comprising a stationary edge rest, a coöperating movable edge rest and means for locking said rests in predetermined relation to each other.
- 75 17. A gage for a rotary cutter comprising separable edge rests and means for preventing separation of said rests when operating on certain portions of the work.
- 80 18. A gage for a rotary cutter comprising a movable edge rest and means acting automatically, as successive portions of the work are presented to the cutter, to limit the movement of said rest and to release the rest again.
- 85 19. A trimming machine comprising in combination a rotary cutter, a stationary edge rest and a coöperating yielding edge rest mounted for swinging movement in a plane parallel to the plane of rotation of the cutter.
- 90 20. A gage for a rotary cutter comprising a plurality of edge rests located adjacent the cutter and means for effecting a simultaneous adjustment of said rests toward or from the periphery of said cutter.
- 95 21. A gage for a rotary cutter comprising a slidably mounted frame adjustable relatively to the cutter and a plurality of edge rests carried by said frame and located adjacent to said cutter.
- 100 22. A gage for a rotary cutter comprising a frame adjustable transversely to the cutter shaft, an edge rest adjustably mounted on said frame, and a second edge rest yieldingly mounted on said frame.
- 105 23. A gage for a rotary cutter comprising a movable edge rest, a device engaging the work and a stop carried by said device arranged to engage the rest to limit its movement.
- 110 24. A gage for a rotary cutter comprising a yielding edge rest, a device yieldingly engaging the work and a stop carried by said device and arranged to engage said rest to limit its movement in one direction.
- 115 25. A gage for a rotary cutter comprising a yielding edge rest, a device yieldingly engaging the work, a stop carried by said device arranged to engage the rest to limit its

movement and means for effecting a relative adjustment of said stop and edge rest.

26. A gage for a rotary cutter comprising an edge rest normally stationary with reference to the cutter, a yielding edge rest and a locking device adjacent to said yielding edge rest.

27. A gage for a rotary cutter comprising an adjustable frame and an edge rest normally stationary with reference to said cutter, a yielding edge rest, a locking device adjacent to said yielding rest, said edge rests and device being arranged to engage the work.

15 28. A gage for a rotary cutter comprising a frame, an edge rest carried thereby and normally stationary with reference to the cutter, a yielding edge rest pivoted to the frame in approximate alinement with the axis of the cutter and a yielding stop-controlling finger pivoted on the frame eccentric to the cutter and carrying a stop arranged to engage the yielding rest.

25 29. A gage for a rotary cutter comprising a frame, an edge rest carried thereby and normally stationary with reference to the cutter, a yielding edge rest pivoted on the frame, a yielding finger carried by the frame and positioned adjacent to the yielding rest, said rests and finger being arranged

to engage the work, a stop adjustably mounted on the finger and means for adjusting said finger relatively to the work.

30. A gage for a rotary cutter comprising a frame, a stationary edge rest, a coöperating movable edge rest, and means for moving said members out of alinement with the cutter to permit removal of the latter.

31. A gage for a rotary cutter comprising a head, a frame adjustably mounted on the head and a plurality of edge rests carried by the frame.

32. A trimming machine comprising a rotary cutter, a gage-carrying head pivoted to the machine standard, a frame mounted on said head and adjustable transversely of the shaft of the cutter, a normally stationary edge rest adjustably and pivotally carried by the frame, a segmental yielding edge rest pivoted to the frame, a yielding finger also pivoted to the frame and a stop device adjustably mounted on said finger and arranged to engage the yielding rest.

In testimony whereof I have signed my name to this specification in the presence of 55 two subscribing witnesses.
